DRAFTING INSTRUMENT

Samuel McFarland Coffman and James Edwin Bell, Jr., Kansas City, Mo.; said Coffman assignor to said James Edwin Bell, Jr.

Application March 2, 1940, Serial No. 221,960

10 Claims. (Cl. 33—177)

This invention relates to engineering instruments and particularly to drafting equipment in the nature of a drafting instrument, and the primary object is to provide a simple, durable and easily manipulated device which may be employed in describing arcs of a true circle.

One of the important aims of this invention is the provision of a circular drafting instrument which has means visible to the operator, for indicating the degrees of the arc described with relation to four different scales of measurement, each of which is customarily employed in plotting curves most commonly used by engineers.

A yet further aim of the instant invention is to provide a drafting instrument of the aforementioned character wherein is provided a pair of specially disposed rotatable plates, each of which actuates a plurality of connecting rods joined to a flexible strip that is deformed from a normal condition to produce the desired arc as the manually controlled operating means for the aforesaid plates is manipulated.

A still further object of the instant invention is to provide an inexpensive, light, convenient, and unique drafting instrument, usable in plotting curves and for indicating the degrees of the curves in terms based upon a number of commonly used scales of measurement.

This invention has for a further object the provision of a drafting instrument of the aforementioned character wherein is incorporated a compensating track for moving the ends of a number of rods toward and from a common center about which they are being rotated as such rotation occurs.

Other objects of the invention will occur to one skilled in the art when the preferred embodiment of the invention is understood through a reading of the following specification, which refers to the accompanying drawing wherein:

Figure 1 is a top plan view of a drafting instrument, made in accordance with the present invention, parts being broken away for clearness.

Fig. 2 is an inverted fragmentary elevational view of the drafting instrument.

Fig. 3 is a vertical cross sectional view taken on line III—III of Fig. 1.

Fig. 4 is a fragmentary detailed sectional view taken on line IV—IV of Fig. 1.

Fig. 5 is a fragmentary cross sectional view taken on line V—V of Fig. 2; and

Fig. 6 is a similar view through a portion of one of the connecting rods taken on line VI—VI of Fig. 2.

In the preferred form of the invention, a flexible strip 10 forms a guiding edge for the drafting instrument after the same has been deformed and bent to create an arc of a circle through the medium of a plurality of connecting rods 12. Strip 10 is mounted upon a body 14 in the nature of a case through the upper wall 16 of which is formed a number of sight openings 18, through which to view an underlying scale 20 having indicia 22 thereon.

Body 14 is in the form of a plate or planar element having notches 24 formed inwardly from the arcuate edge thereof to accommodate certain parts of the connecting rods 12.

A nose block 26 carried by body 14 is bifurcated at its outermost part and receives transverse lug 28 to hold strip 10 in place. A pin 30 is employed to secure lug 28 and nose block 26 in assembled relation. Nose block 26 engages strip 10 at a point intermediate its ends and preferably at a place midway between the free ends thereof so that balance may occur, and further, so that connecting rods 12 on each side of nose block 26, may operate efficiently. In practice it has been found desirable to use a strip substantially 18 inches long.

The ends of connecting rods 12 are secured to strip 10 through the medium of a yoke 32 and turn-buckle 34. Yoke 32 has a screw-threaded stem 36 extending into turn-buckle 34 and one end of connecting rod 12 is screw-threaded in a direction opposite to the threads on stem 36 which likewise projects into turn-buckle 34 so that the length of the respective connecting rods 35 may be altered to adjust strip 10.

The legs of yoke 32 embrace an ear 38 secured to one side of strip 10 and a pin 40 pivotally secures together yoke 32 and ear 38. When the rear face of strip 10 is drawn against the edge of body 14, yoke 32 finds clearance by entering a notch 24.

A vertical spindle 42 is mounted on body 14 with the ends thereof disposed on opposite sides of said body to support the upper plate 44 and a lower plate 46. These plates are pivotally mounted upon spindle 42 for free movement about the axis thereof and upper plate 44 has a gear segment 48 formed thereon, while a gear segment 50 is formed on plate 46. A pinion 52 is pivotally mounted upon axle 54 is in mesh with gear segments 48 and 50 so that as one plate is rotated about the axis of spindle 42, the other plate will move about said axis in an opposite direction.

Scale 20 is mounted upon spindle 42 for movement therewith and in the same direction as upper plate 44.

Each plate 44 and 46 respectively is reduced in width to form a stem 56 and 58 respectively. It is to this portion of the plates that the inner ends of connecting rods 12 are secured.

As illustrated in Figs. 4 and 5, connecting rods 12 are not directly secured to these stem portions 56 and 58 respectively but are slidably mounted thereon through the medium of a tubular element 60 and 62 respectively. Upper plate 44, for example, has tubular element 60 mounted thereon as illustrated in Fig. 4. The inner ends of connecting rods 12 are joined to element 60 by screws or analogous means 64 and an operating lever 66 is attached to stem portion 56. Lever 66 has its inner end pivotally secured to spindle 42 while the outer end thereof is notched as at 68 to ride over an arcuate track 70 concentric with the axis of spindle 42. If desired, the outer end of this operating lever 66 may have means for securing the same in place along track 70 and since any desirable mechanism may be employed for this purpose, the same is not here detailed but shown to be a housed clutch engaging track 70 and operated by exposed buttons 72.

A compensator must be included in the instrument because the path of travel followed by any one of the points of connection between elements 60 and 62 and the several connecting rods 12, is not a true arc but a path of travel having different radii as the strip is flexed to form arcs of different degrees.

35 The effective lengths of rods 12 are changed as plates 44 and 46 are moved about their common axis of rotation. To accomplish this end, the tubular element 60 to which is attached arms 12 on one side of nose 26, is moved toward and from spindle 42 through the medium of guide 74. This guide 74 has a slot 76 provided therein and block 78 pivotally mounted as at 80 to tubular element 60 rides in slot 76. Slot 76 is not concentric with spindle 42 and therefore, as operating lever 66 is manually manipulated, the effective length, and therefore the action by rods 12 upon strip 10, will be altered to dispose said strip 10 in a proper position as curves of different degrees are formed.

50 Lower plate 46 is formed in precisely the same manner as upper plate 44 in that it has an extended portion 58 slidably retained in tubular element 62. Arms 12 on the opposite side of nose 26 from those carried by member 56, are attached to member 62 so that as plate 46 is rotated about the axis of spindle 42, tubular element 62 will be moved toward and from spindle 42 to create the proper effect upon rods 12 so as to produce a curve having an accurate radius.

60 Lower tubular element 62 has a block 82 mounted thereon to ride in slot 84 of guide 86. This guide 86 is on one side of body 14 while guide 74 is mounted on the opposite side thereof. Feet 88 support the instrument upon the surface being worked on and the lower edge of strip 10 is relatively close to this surface so that a pencil or the like may be drawn along the front side of strip 10 after it has been positioned to present the curve desired.

70 It is desirable to use scales of 1 in. to 100 ft., 1 in. to 200 ft., 1 in. to 300 ft., and 1 in. to 400 ft. The indicia 82, visible through windows 18 of the upper wall 16, will indicate to the operator the degree of curve with respect to these several scales of measurement and any suitable designa-

tions visible through these windows may be marked upon the underlying flat scale 20. Numerals 23 on wall 16 adjacent to each window 18, indicate the particular scale to which the underlying indicia 22 relates.

5 Light materials should be used in producing the instrument and since it is to be employed on a drawing board, the operating means is confined to a single element that may be manipulated by one hand.

10 This application is a continuation in part of a case previously filed by James E. Bell, Jr., Serial No. 278,054, filed June 8, 1939, covering improvements for Curve plotting instrument.

15 Having thus described the invention, what is claimed as new and desired to be secured by Letters Patent is:

1. An instrument of the character described comprising a flexible strip; a planar body having a nose engaging the medial point on the strip; a pair of plates rotatably mounted on the body; means for rotating the plates in opposite directions about a common axis; and a plurality of connecting rods joining the plates and said strip for drawing the same into an arched condition as the plates are simultaneously rotated.

2. An instrument of the character described comprising a flexible strip; a planar body having a nose engaging the medial point on the strip between the ends thereof; a pair of plates rotatably mounted on the body; means for simultaneously rotating the plates in opposite directions at the same rate of speed about a common axis; a plurality of connecting rods joining the strip, between said nose and one end thereof, with one of the plates; and a plurality of connecting rods joining the strip, between said nose and the other end thereof with the other plate whereby when the plates are actuated by the rotating means, the strip is drawn into an arc of a circle.

3. An instrument of the character described comprising a flexible strip; a planar body having a nose engaging the strip intermediate its ends; a pair of plates rotatably mounted on the body; means including an operating lever for simultaneously rotating the plates in opposite directions at the same rate of speed about their axes; a plurality of connecting rods joining the strip, between said nose and one end thereof, with one of the plates; and a plurality of connecting rods joining the strip, between said nose and the other end thereof with the other plate.

4. An instrument of the character described comprising a flexible strip; a body having a nose engaging the strip intermediate its ends; a pair of plates rotatably mounted on the body; means for simultaneously rotating the plates in opposite directions at the same rate of speed about a common axis; a plurality of connecting rods joining the strip, between said nose and one end thereof with one of the plates; a plurality of connecting rods joining the strip, between said nose and the other end thereof, with the other plate; a plurality of scales rotatably mounted for movement with one of said rotatable plates; and a housing for the scales having sight windows formed therein for viewing the scales.

5. An instrument of the character described comprising a flexible strip; a case having a nose engaging the strip intermediate its ends; a pair of plates rotatably carried by the case; means for simultaneously rotating the plates in opposite directions at the same rate of speed about a common axis; a plurality of connecting rods

joining the strip, between said nose and one end thereof, with one of the plates; a plurality of connecting rods, joining the strip between said nose and the other end thereof, with the other plate; and a plurality of scales rotatably mounted for movement with one of said rotatable plates, said case having sight windows formed therein for viewing the scales, each of said scales being arranged to indicate to the operator the 10 degree of the arc described by said strip in relation to a scale of measurement different from the remaining scales.

6. An instrument of the character described comprising a flexible strip; a case having a nose 15 engaging the strip intermediate its ends; a pair of plates rotatably carried by the case; a gear segment on one of the plates; a pinion in mesh with the gear segment; an operating lever for 20 rotating the said one plate; a gear segment on the other plate in mesh with the pinion whereby to interconnect the plates for simultaneous movement in opposite directions about a common axis at the same rate of speed; a plurality of connecting rods joining the strip 25 between said nose and one end thereof with one of the plates; a plurality of connecting rods joining the strip between said nose and the other end thereof with the other of said plates; and a scale movable as the strip is flexed to indicate 30 the degree of curvature of said strip in relation to a number of scales of measurement.

7. An instrument of the character described comprising a flexible strip; a case having a nose engaging the strip intermediate its ends; a pair 35 of plates rotatably carried by the case; a gear segment on one of the plates; a pinion in mesh with the gear segment; an operating lever for rotating the said one plate; a gear segment on the other plate in mesh with the pinion whereby 40 to interconnect the plates for simultaneous movement in opposite directions about a common axis at the same rate of speed; a plurality of connecting rods joining the strip between said nose and one end thereof with one of the plates; a plurality of connecting rods joining the strip 45 between said nose and the other end thereof with the other of said plates; and a scale movable as the strip is flexed to indicate its degree of curvature, the ends of said connecting rods

joining the strip on one side of the nose being respectively the same distance from said nose as the ends of the connecting rods on the other side thereof, said connecting rods of both plates having the other ends thereof joined thereto 5 by means for moving the same toward and from the axis of rotation of the plates as the plates are rotated.

8. An instrument of the character described comprising a flexible strip; a body having a nose 10 engaging a point on the strip between the ends thereof; a pair of members rotatably mounted on the body; manually operable means for rotating the plates in opposite directions about a common axis; a plurality of connecting rods 15 joining the plates and said strip for drawing the same against the nose and into an arched condition as the plates are simultaneously rotated; and means for altering the effect of at least one of the connecting rods on the strip as the arm 20 is moved about the axis of rotation with its associated plate.

9. An instrument of the character described comprising a flexible strip; a body having a nose 25 engaging a point on the strip between the ends thereof; a pair of members rotatably mounted on the body; manually operable means for rotating the plates in opposite directions about a common axis; a plurality of connecting rods joining the plates and said strip for drawing the same 30 against the nose and into an arched condition as the plates are simultaneously rotated; means slidably mounted on each plate respectively for establishing connection between certain of said arms and the plate; and an element for moving 35 the said means and the associated arms toward and from the axis of rotation as the plates are rotated.

10. In an instrument of the character described, a flexible strip; a plurality of arms each 40 having one end thereof joined to the strip and the other ends thereof mounted for movement in paths of travel about a fixed axis; and means for moving said other ends of said arms toward and from the axis as the same are moved there- 45 around.
